PAUL FREYGANG, OF SAN FRANCISCO, CALIFORNIA.

METHOD OF PACKAGING MERCHANDISE.

1,258,887.

Specification of Letters Patent. Patented Mar. 12, 1918.

Application filed October 17, 1917. Serial No. 197,035.

To all whom it may concern:

Be it known that I, PAUL FREYGANG, a citizen of the United States, residing at the city and county of San Francisco and State 5 of California, have invented certain new and useful Improvements in Methods of Packaging Merchandise, of which the following is a specification.

The hereinafter described invention relates to an improved method of packaging perishable merchandise, such as coffee, tea, prunes, raisins and tobacco and similar dry articles in order to preserve the full flavor 10 of the commodity and prevent the same from becoming affected in any manner whatsoever by moisture or climatic conditions, while at the same time protecting the contents of the package from deterioration of any kind whatsoever so long as the package 15 remains in its sealed condition; the invention permitting perishable goods to be placed or sealed within non-metallic vessels for shipment and transportation with the assurance that full protection will be given 20 to the contents thereof until such times as the package is opened.

In carrying out the invention the commodity to be merchandised or packaged is primarily enveloped within a moisture 25 proof lining in order to protect the same against absorption of the moisture contained therein. This lining or casing is preferably applied to the goods prior to the placing of the same within the casing or 30 envelop, which is composed of an inner fibrous liner and outer fibrous lining, there being interposed between the said inner and outer lining a metallic lining. This inclosing envelop has the ends thereof folded 35 down to partially seal or envelop the merchandise, the final laps of the interfolded ends of the envelop being pasted down or sealed in the usual manner to secure the 40 ends of the package closed. After the merchandise has been inclosed or sealed within the package as described, the closed ends thereof are hermetically sealed by means of suitable end pieces which are united to the closed end of the package by an adhesive 45 compound impervious to moisture, the ends being applied under pressure so as to firmly seat or embed the same so as to speak, with-

in the end walls of the package proper, the package during such time as such pressure is brought to bear thereon for the purpose 55 of applying or firmly seating the ends, being held within a suitable clamp or form mold which protects the side walls of the package against bursting or breaking by reason of the end pressure brought to bear against the 60 contents thereof.

For a full understanding of the invention, reference should be had to the accompanying sheet of drawings, wherein,

Figure 1 is a broken perspective view of 65 the package with its sealed contents.

Fig. 2 is a perspective view of one of the sealing ends separated from the package.

Fig. 3 is a broken detailed view of the package with one of its ends open and with 70 the contents removed therefrom.

Fig. 4 is a broken perspective view illustrating the package to be sealed within a forming mold and with the hermetic ends 75 positioned for seaming.

In the drawings, the numeral 1, is used to designate the inner non-absorbent liner for the package and which embraces or incloses the goods to be packaged, and 2, the inner fibrous liner for the packing envelop proper and which lies in contact with the inner non-absorbent liner 1. The outer wall or covering 3 of the packing envelop is preferably formed of fibrous material and there is interposed between the inner liner wall 2, 80 and the outer wall covering 3, the metallic layer or liner 4, preferably formed of sheet lead. These members are arranged in the usual form of a side sealed envelop, the ends thereof interfolded in the manner similar 85 to any package envelop adapted to surround or embrace merchandise to be packaged. The sealing ends 5 of the package are preferably formed of heavy card board and are provided with the beveled edges 6. In the 90 sealing of the goods after the same have been placed within the inclosing envelop and the projecting ends thereof overlapped or interfolded so that the last layer 7 thereof overlaps the interfolded side walls and 95 secured thereto by suitable paste, the ends 5 are applied by first having their inner or under surface evenly coated with a liquid adhesive impervious to moisture, and the 100

said ends are then properly positioned to cover the ends of the package and then subjected to pressure or rather pressure is placed endwise to the package while the 5 ends 5 are applied thereto, so as to press the ends 5 firmly to a secure seat, this end pressure embedding the ends 5 so to speak, within in the surrounding edges of the ends of the package, the applied pressure securely and 10 evenly distributing the adhesive compound applied to the under face thereof, and the said pressure maintained for approximately two or three minutes or until the impervious adhesive compound is thoroughly dried. 15 During this pressure applying operation, the package with the contents inclosed therein is held within a suitable forming mold 7' while the pressure plates 8 are brought to bear onto the applied ends 5, which said 20 mold prevents the end pressure applied for the sealing of the ends 5 from causing a bursting or tearing apart of the walls of the package, which otherwise would occur on the severe endwise strain to which the 25 contents thereof are subjected on the pressure being applied, or, which if it did not cause a rupture of the walls of the package would at least cause such a bulging thereof as to prevent an attractive appearance to the 30 sealed package.

I have found that perishable merchandise when packaged in the manner set forth is rendered impervious to moisture even when placed within water for a number of hours, 35 in fact, coffee so packaged has been submerged within water at a temperature of 125 degrees Fahr., and maintained so submerged for a period of over 20 minutes and on the removal thereof from the bath the package 40 opened and the contents thereof found to be in perfect condition. Prunes so packaged were submerged in water at a temperature of 75 degrees Fahr. and maintained so submerged for a period of one hour and a 45 half, and after removal and opening of the package the contents thereof found to be in perfect condition, and tobacco so packaged has been subjected to similar tests with the result that the contents of the package were 50 in no manner whatsoever affected by the water.

By the described method of packaging the goods, the same are placed in condition for easy and ready handling and shipment, and 55 such shipment is rendered less expensive than where the merchandise is sealed within heavy metallic containers.

It will be noted that on the sealing ends 5 being applied, that there is formed between 60 the end flaps of the package and the side walls thereof, and the under face of said ends, a layer 9 of the adhesive material impervious to moisture and inasmuch as the side walls of the envelop are rendered mois-

ture proof by reason of the metallic lining 65 interposed between the inner and outer lining or covering of the envelop or package, that on the ends 5 being properly applied thereto under pressure, there is formed a perfect hermetic seal for the closed ends of 70 the envelop, and the same thus rendered moisture proof during such times as the package remains in its sealed condition.

The described invention will appeal to those desirous of placing their merchandise 75 before the public in such a manner that deterioration thereof cannot take place at any time prior to the opening of the package and this irrespective as to whether the package may be subjected to moisture or not, inasmuch as the aromatic flavor of the goods is maintained and the goods presented to the customer with the full freshness and flavor possessed thereby prior to the packaging thereof. 80

If so desired, the outer covering 2, of the envelop may have applied to the inner face thereof a coating of paraffin, but such is believed to be unnecessary where the metallic liner wall is employed and introduced between the inner and outer walls 1 and 2 of the envelop. The essential feature of the invention resides in the hermetic sealing ends 5, with the impervious adhesive applied between the inner surface thereof and 95 the exterior surface of the final lap of the ends of the envelop, inasmuch as it is these ends with the impervious adhesive applied under pressure for uniting the same to the closed package which forms the hermetic 100 seal and prevents moisture penetrating through the ends of the package to the interior thereof and by so doing protecting the contents against damage. 90

Having thus described the invention 105 what is claimed as new and desired to be protected by Letters Patent is:

1. The method of packaging perishable merchandise, which consists in inclosing the same within an envelop formed of an inner 110 and outer wall covering separated by a moisture proof liner interposed therebetween, interfolding the ends of the package over the goods placed therein, and applying under pressure to the ends so closed hermetic sealing ends having introduced between the under surface thereof and the outer surface of the ends of the package an impervious adhesive and maintaining the ends under such applied pressure until the 115 adhesive becomes dried. 120

2. The method of packaging perishable merchandise, which consists in first inclosing the article within a non-absorbent wrapping, thence placing the same within a 125 moisture proof envelop having an inner and an outer wall covering separated by a moisture proof lining and interfolding the ends

of the envelop to inclose the wrapped goods, thence hermetically sealing the closed ends by applying thereto under pressure sealing end pieces having a coating of an impervious adhesive applied to the under surface thereof and maintaining the same under pressure until the adhesive becomes dried.

In testimony whereof I have signed my name to this specification in the presence of two subscribing witnesses.

PAUL FREYGANG.
